RESILIENT GUN RECOIL PAD

Edward L. Morrow, Fairfield, Conn., assignor to Olin Mathieson Chemical Corporation, a corporation of Virginia

Filed Feb. 12, 1968, Ser. No. 10,524

Term of patent 14 years

Int. Cl. D22—02

U.S. Cl. D22—9

FIG-2

FIG-1

FIG-3

FIG-4

FIG-5

FIGURE 1 is an elevational view of one side of a resilient gun recoil pad embodying our new design, the opposite side of the pad being the mirror image of that illustrated;

FIGURE 2 is a front elevation of the pad;

FIGURE 3 is a rear elevation of the pad;

FIGURE 4 is a bottom plan view of the pad; and

FIGURE 5 is a top plan view of the pad.

I claim:

The ornamental design for a resilient gun recoil pad, as shown and described.
